UNITED STATES PATENT OFFICE.

ARTHUR JONES, OF BELLEVILLE, ILLINOIS, ASSIGNOR TO U. S. SMELTING FURNACE COMPANY, OF BELLEVILLE, ILLINOIS, A CORPORATION OF ILLINOIS.

BURNER STRUCTURE FOR FURNACES.

Application filed April 12, 1924. Serial No. 706,031.

To all whom it may concern:

Be it known that I, ARTHUR JONES, a citizen of the United States of America, residing at the city of Belleville, county of St. Clair, State of Illinois, have invented a certain new and useful Burner Structure for Furnaces, of which the following is such a full, clear, and exact description as will enable anyone skilled in the art to which it applies to make and use the same, reference being had to the accompanying drawings, forming part of this specification.

My invention relates to a burner structure for furnaces and particularly to improvements in that form of structure shown and described in my prior application, Serial No. 591,804, filed October 2, 1922.

One object of the present invention is to so construct the device that the blocks of refractory material of which it is composed will not only be more easily and cheaply manufactured, but will also be so shaped and proportioned as to better withstand the extremely high temperature to which they are subjected during the operation of the furnace. Another object of my invention is to provide a sliding connection between the furnace and burner structure to obviate the necessity of moving one of such parts toward and away from the other to connect and disconnect them.

In the accompanying drawings, which illustrate one form of burner structure made in accordance with my invention, Figure 1 is a vertical central section; Figure 2 is a view showing the details of the central or pipe junction block; Figure 3 is a view showing the details of the end block of the connector; Figure 4 is a view showing the details of the inner burner sleeve; Figure 5 is a view showing the details of a section of pipe protecting collar; Figure 6 is a view showing the details of the outer burner sleeve; and Figure 7 is a section taken on the line 7-7 of Figure 1.

The end of the furnace is indicated at 10. This furnace may be similar to that shown and described in my prior application, above referred to. The casing 11 of the burner structure is preferably rectangular and formed of brick work so as to produce a chimney-like structure through which passes the air supply pipe 12. An extension 13 of the pipe 12 is closed at its lower end by a cap 14. 15 is a forwardly extending section, and

16 a rearwardly extending section of burner pipe. In the burner pipe is an adjustable burner 17. Pipes 12, 13, 15 and 16 communicate by means of a cross connector 18.

Surrounding the cross connector 18 is a pipe junction block 19 of refractory material such as fire clay. This block is composed of eight similar parts adapted to fit around the pipes and connector and to be held together by the engagement of the tapered bosses 20 with other parts to be described. Arranged above the block 19 and surrounding the pipe 12 is a pipe protecting collar 21, shown in detail in Figure 5. The collar is composed of two parts each provided with interlocking lugs 22 and 23 so as to hold the parts firmly together when in position on the pipe. Formed in one end of the collar 21 is a tapered recess 24 adapted to receive one of the bosses 20 for engagement with the recess of a second section of collar. While I have shown but one section of collar 21 in the drawings, it may be found necessary to use two or more sections to protect the pipe 12 from the heat of the escaping products of combustion. Arranged around the pipes 13 and 16 are collars 21' similar in all respects to the collar 21 except that the boss 25 is omitted. The collar 21' surrounding the pipe 13 is supported on a plate 26 built into the casing 11 and provided with a central opening for the passage of the pipe 13. As it is difficult, if not impossible, to so construct the parts as to insure the collars 21' bearing properly on the plate 26, a space is left between said parts which is filled by a shim 27 of the proper thickness.

The forwardly projecting portion 15 of the burner pipe is covered by an inner burner sleeve divided longitudinally into two parts 28 and 29. The part 28 is divided into four sectors each provided with a rib 30, and the part 29 is similarly divided and provided with ribs 31. These ribs 30 and 31 serve to space the outer burner sleeve from the inner sleeve to form flues 32 (Figure 7) for the passage of the products of combustion from the furnace to the space within the casing 11. Formed in one end of the member 28 is a recess 33 adapted to receive one of the bosses 20 on the block 19 and this function, together with the collars 21 and 21' to hold the parts of said block together. Formed on the other end of the

member 28 is a boss 34 engaging with a corresponding recess in the part 29. As shown in Figure 6 the outer burner sleeve comprises two parts 35 and 36 each preferably formed of six sectors and held together by a metal ring 37 abutting at one end against a flange 38 on the part 36, while the other end is provided with a flange 39 bolted to a plate 40 carried on the casing 11.

10 The ring 37 forms a bearing for the sliding annular connector extending between the burner structure and the furnace 10. This connector comprises a shell and a lining. The shell 41 is provided at one end 15 with a flange 42 adapted to engage the end of the furnace, and at the other end with a flange 43 adapted to bear on the ring 37, one of said flanges being removable to allow of the insertion of the lining. Such lining 20 consists of two annular parts 44 and 45 each preferably formed of six sectors and the part 44 being recessed at 46 (Figure 3) to receive the flange 42. It will be evidenced that by sliding the connector longitudinally on the ring 37 the burner structure may 25 be engaged with or disengaged from the furnace.

Having fully described my invention, what I claim as new and desire to secure by 30 Letters Patent of the United States is:

1. In a device of the class described, the combination with a flue structure, of a center block therein composed of separable parts, a pipe connection surrounded by said 35 center block, a burner extending from said connection, and a covering for said burner, said covering being arranged to allow the return of gases to the flue structure.

2. In a device of the class described, the 40 combination with a flue structure, of a center block therein composed of separable parts, a pipe connection surrounded by said center block, a burner extending from said connection, a sleeve surrounding said burner, and composed of separable parts, and a second 45 sleeve surrounding said first named sleeve and separated therefrom to form a gas return passage.

3. In a device of the class described, the 50 combination with a burner structure, of a center block therein composed of separable parts, a pipe connection surrounded by said center block, a burner extending from said connection, a sleeve surrounding said burner, and composed of separable parts, a second 55 sleeve surrounding said first named sleeve and separated therefrom to form a gas return passage, said second named sleeve being also composed of separable parts, and a member surrounding said second named sleeve and holding the parts thereof together.

4. In a device of the class described, the 60 combination with a burner structure, of a center block therein composed of separable

parts, a pipe connection surrounded by said center block, a burner extending from said connection, a sleeve surrounding said burner and composed of separable parts, a second sleeve surrounding said first named sleeve and separated therefrom to form a gas return passage, said second named sleeve being also composed of separable parts, and a member surrounding said second named sleeve and holding the parts thereof together, said member being secured to the wall of the flue structure. 70

5. In a device of the class described, the combination with a flue structure, of a center block therein composed of separable parts and provided with a plurality of bosses, and pipe protecting members engaging with said bosses to hold the parts of said center block together. 80

6. In a device of the class described, the combination with a flue structure, of a center block therein composed of separable parts and provided with a plurality of bosses, a pipe connection in said center block, pipe extending from said connection, and pipe protecting members each composed of interlocking parts, said members surrounding the pipes and engaging with said bosses to hold the parts of the center block together. 90

7. In a device of the class described, the combination with a flue structure, of a pipe connection therein, a burner extending forwardly from said pipe connection, a covering of refractory material for said connection and burner, a portion of said covering projecting beyond the flue structure and being provided with a return passage for conducting gases to the flue structure, and a furnace connector sliding on said projecting portion. 100

8. In a device of the class described, the combination with a flue structure, of a pipe connection therein, a burner extending forwardly from said pipe connection, a covering of refractory material for said connection and burner, a portion of said covering projecting beyond the flue structure and being provided with a return passage for conducting gases to the flue structure, and a furnace connector sliding on said projecting portion, said connector comprising a shell and a refractory lining composed of a plurality of parts. 110

9. In a device of the class described, the combination with a burner structure, of a pipe connection therein, a burner extending from said connection, a sleeve surrounding said burner and composed of separable parts, a second sleeve surrounding said first named sleeve and separated therefrom to form a gas return passage, said second named sleeve being also composed of separable parts, a member surrounding said second named sleeve and holding the parts thereof 120

125

130

together, and a furnace connector slidingly mounted on said member.

10. In a device of the class described, the combination with a burner structure, of a 5 pipe connection therein, a burner extending from said connection, a sleeve surrounding said burner and composed of separable parts, a second sleeve surrounding said first named sleeve and separated therefrom to form a gas 10 return passage, said second named sleeve being also composed of separable parts, a member surrounding said second named sleeve and holding the parts thereof together, and a furnace connector slidingly 15 mounted on said member, said connector comprising a shell and a refractory lining composed of a plurality of parts.
11. In a device of the class described, the

combination with a flue structure, of a center block therein composed of separable 20 parts and provided with a plurality of bosses, a pipe connection surrounded by said block, pipe protecting members engaging with said bosses to hold the parts of said block together, a burner extending from said connection, a sleeve surrounding said burner and composed of separable parts, a second 25 sleeve surrounding said first named sleeve and separated therefrom to form a return passage, a member surrounding said second 30 named sleeve and holding the parts thereof together, and a furnace connector slidingly mounted on said member.

In testimony whereof, I have hereunto set my hand this the 1st day of April, 1924.

ARTHUR JONES. [L. S.]
